OSCAR WOODWARD, OF BABYLON, NEW YORK, ASSIGNOR TO REMINGTON TYPE-WRITER COMPANY, OF ILION, NEW YORK, A CORPORATION OF NEW YORK.

TYPEWRITING-MACHINE.

1,375,764.

Specification of Letters Patent. Patented Apr. 26, 1921.

Application filed November 13, 1919. Serial No. 337,633.

To all whom it may concern:

Be it known that I, OSCAR WOODWARD, citizen of the United States, and resident of Babylon, in the county of Suffolk and State 5 of New York, have invented certain new and useful Improvements in Typewriting-Machines, of which the following is a specification.

The object of my present invention is to 10 provide new and improved means for securing a fulcrum or pivot wire on its support in a typewriting machine so that said pivot wire will be maintained in a relatively fixed position at all times and will not be disturbed or displaced as the result of the actuation of type bars or other parts fulcrumed on it.

As heretofore constructed typewriting machines employing type bars mounted on 20 a common pivot wire or fulcrum have had such pivot wire arranged in a groove, slot-way or seat in the type bar support or segment. In such cases where the pivot or fulcrum wire fits loosely in its groove or seat it 25 is liable to displacement or to shift its position sidewise, during the operation of the type bars, with consequent poor alinement. When it is attempted to remedy this defect by making a very tight fit between the pivot 30 wire and its bearing or seat, it is found to be extremely difficult to force the wire or member in and out of place. Also, devices have heretofore been provided for tightening or 35 fixing the pivot wire but such prior devices have been open to various objections such as liability to cause breakage of the segment or distortion of it or of the pivot wire itself. These troubles have been primarily due to the fact that the tightening devices were 40 screwed in or otherwise applied to an excessive extent. My present invention aims to overcome these defects and to provide a comparatively simple but efficient pivot wire 45 tightener which may be readily applied to existing styles of typewriting machines. In carrying out my invention I provide a construction in which the effect of the tightening means is limited so that it cannot be applied to an excessive or harmful extent. 50 This is done by providing an elastic, resilient or spring element which coöperates with the tightener to limit the amount of pressure that can be conveyed by the tightener

to the pivot wire. Stated in another way, 55 resilient or elastic means are employed for pressing the pivot wire against its bearing or support, the pressure being limited by the forcing effect of which the spring means is capable.

To the above and other ends which will 60 hereinafter appear, my invention consists in the features of construction, combinations of devices, and arrangements of parts hereinafter described and particularly pointed 65 out in the claims.

In the accompanying drawings,

Figure 1 is a fragmentary front to rear 70 sectional view of the type action, mounting and associate parts of a typewriting machine embodying one form of my present invention.

Fig. 2 is a front elevation of the type bar support or segment showing the pivot wire mounted thereon and with my invention applied at its end portions. 75

Fig. 3 is an enlarged fragmentary front view of one end of the segment, parts being broken away to illustrate my invention more clearly.

Fig. 4 is a fragmentary top plan view of 80 an end portion of the segment illustrating the slot or groove for the fulcrum wire.

Fig. 5 is a top plan view of Fig. 3 but with the nut or fulcrum wire tightener sectioned away. 85

Figs. 6 and 7 are views corresponding to Fig. 5 but showing modified forms of the flat spring or resilient element.

Fig. 8 is a view corresponding to Fig. 3 but showing a modification. 90

The machine to which my invention is shown as applied is disclosed more fully in my patent dated June 8, 1920, No. 1,342,489. On the top plate 1, which is comprised in the main frame, there is suitably secured a 95 vertically disposed type bar support or segment 2 which is provided with a series of radial slots 3 in which are arranged front strike type bars 4. These type bars are fulcrumed or pivoted on a common fulcrum or pivot wire 5 which is supported on the segment 2 in a manner hereinafter specifically described. The set or series of type bars are normally supported in substantially horizontal positions on a type rest 6, and 100 are adapted to coöperate with the front face

of a platen 7, diagrammatically illustrated. In printing position the type bars coöperate with a center guide 8 which is secured to the front upper portion of the segment 2. 5 Type bar actuating devices are provided for each type bar which coöperate with a slot 9 formed in the heel portion of the bar, said devices comprising a headed pin 10 engaging in said slot, said pin projecting laterally from the upper end portion of the vertically disposed arm of a lever 11 having a stationary pivot 12. The short horizontally disposed arm of said lever is connected by a link 13 with a key lever 14, the 10 set of key levers being arranged within the base portion 15 of the main frame.

The fulcrum or pivot wire 5 is curved or arcuate and its bearing as best shown in Figs. 3 and 4, is a correspondingly curved or 20 arcuate slot-way or groove 16 cut or otherwise formed in the rear face of the segment plate or support 2. The opposite curved walls 16^a and 16^b of the bearing or slot-way are slightly depressed or cut away on curves 25 corresponding to the pivot wire which is as usual circular in cross section. The form and dimensions of the seat or slot-way are such that the pivot wire does not fit tightly therein but is loose enough to be readily 30 slid, pushed or pulled into and out of place.

In order to do away with objectionable looseness of the pivot wire on its support or bearing, I provide novel means for forcing or pressing the pivot wire against its bearing to an extent sufficient to fix the pivot wire in place so that it will provide an unvarying point of pivotal support for all of the type bars that are fulcrumed on it. In the present instance the pivot wire tightener or securing devices are applied to each 40 end of the pivot wire where it projects above the upper horizontal face of the type bar segment 2, and this duplication of devices is preferred although not essential to 45 the carrying out of my invention in all instances. As shown in Figs. 2 and 3 the upper projecting end portions of the pivot wire 5 are reduced to provide coned portions 5^a which terminate in threaded tips or 50 ends 5^b. Each threaded end receives a pivot wire tightener or nut 17 which may be screwed down on the threaded end 5^b until arrested by the upper end of the cone 5^a. Interposed between the body portion 55 or pivot wire proper 5 and the nut or tightener 17 is an elastic or resilient member or element which in the present instance is in the form of a flat spring or spring plate 18. The free end portion of the spring member 60 18 is formed with a round hole or opening indicated at 19, which receives the coned portion 5^a of the pivot wire. The springs 18 are arranged on top of the segment and project inward or toward the middle of the 65 segment, the inner end portion of each

spring or member 18 being secured to the top of the segment by a headed screw 20. The inherent tendency of the elastic element 18 is to spring upward away from the top face of the segment 2, and this tendency or 70 tension is transmitted through the nut or tightener 17 to the pivot wire proper 5 which is consequently pressed, pulled or forced upward into contact with the inner or upper face 16^a of the bearing or slot-way 75 16. It will be understood that this pressure or force is increased by tightening or screwing down the tightener or nut 17 at each end of the pivot wire, but the extent to which the nuts can be tightened is limited by the 80 upper ends of the coned portions 5^a. The force or inherent tension or pressing power of the springs or elastic elements 18 is such, and the tighteners or abutments 17 are so related to them and to the associate parts, 85 that even when the tighteners are screwed down to the limit or full extent the pressure of the pivot wire against the upper or shorter wall or face of its bearing is not excessive but is entirely sufficient or adequate 90 to hold the pivot wire in fixed position at all times and to resist displacement due to reactions of the type bars against their points of pivotal support during printing operations. 95

Various changes may be made without departing from the principles of my invention. For example, in Fig. 6 there is illustrated a spring plate 21, differing somewhat from the spring plate 18 of the Figs. 1-5 100 construction in that the spring plate 21 is provided with a slot-way 22 open at its rear. This slot-way fits around the coned portion 5^a of the pivot wire and the spring reacts against the tightener 17 as in the first construction. However, by slightly loosening the screw 20 which holds the spring 21 in place, said spring may be swung forward to the dotted line position so as to clear the pivot wire and its bearing. This construction 105 enables the pivot wire to be withdrawn without entirely removing either of the springs 21. 110

In Fig. 7 is illustrated a further modification of the spring or elastic element. The 115 spring 23 of the Fig. 7 construction is provided with a slot 24 which has a mouth opening at the end of the spring instead of at the side as in the Fig. 6 construction.

A further modification is illustrated in Fig. 8 which shows a pivot wire 25 having a coned portion 25^a, as in the first described construction, but with the threaded end or tip 25^b bent vertically instead of conforming to the general curve of the pivot wire as does 125 the tip 5^b. The Fig. 8 construction enables the tightener or nut 17 which coöperates with the tip 25^b to be horizontally arranged so that it is parallel with the top face of the segment and with the free end portion of 130

the spring 18. Consequently the bottom face of the nut contacts with the upper surface of the spring on all sides instead of only at one side as in the Figs. 1-5 construction.

Other changes will suggest themselves to those skilled in the art.

By my present invention important new and improved results are achieved through

- 10 simple and inexpensive means which may readily be applied to different styles of typewriting machines and may be adapted to existing makes of such machines with but slight changes. In carrying out my present
15 invention it will be observed that there is provided a pivot wire in combination with a pivot wire tightener and an elastic element coöperating with the tightener to limit the amount of pressure that can be conveyed by
20 the tightener to the pivot wire; that in the present instance a spring plate supported by the type bar support coöperates with the pivot wire to hold it firmly in position by an elastic tension; that an elastic element is
25 arranged between the pivot wire tightener and the pivot wire proper, the construction being such that the amount of pressure that can be conveyed by the tightener is limited to the power of the elastic element; that a
30 spring member or element operates on the pivot wire to control the pressure exerted by the pivot wire against its support; that a resilient means press the pivot wire against its bearing; and that means are provided
35 which act through a spring or resilient member to force the pivot wire against its bearing or seat, the pivot wire in the present instance pressing or pulling against the inner or shorter wall of the slot-way or groove in which it is arranged or seated.

What I claim as new and desire to secure by Letters Patent, is:—

1. In a typewriting machine, the combination of a type bar support, type bars, a pivot wire for said type bars, a pivot wire tightener, and an elastic element coöperating with the tightener to limit the amount of pressure that can be conveyed by the tightener to the pivot wire.
45
50 2. In a typewriting machine, the combination of a type bar support, type bars, a pivot wire for said type bars, a spring plate supported by the type bar support and coöperating with the pivot wire to hold it firmly in position by an elastic tension.
55
60 3. In a typewriting machine, the combination of a type bar support, type bars, a pivot wire for said type bars, said pivot wire being mounted on said support, and a spring plate operative on said pivot wire to control the amount of the pressure exerted by said pivot wire against said support.
65
70 4. In a typewriting machine, the combination of a type bar support provided with a bearing for a pivot wire, a pivot wire,

type bars mounted thereon, and resilient means for pressing said pivot wire against its bearing.

5. In a typewriting machine, the combination of a type bar segment provided with a bearing for a pivot wire, a pivot wire, type bars thereon, a spring, and means acting through said spring to force said wire against said bearing.

6. In a typewriting machine, the combination of a type bar support, type bars, a pivot wire for said type bars, an abutment adjustably connected to said pivot wire, and an elastic member operating through said abutment on said pivot wire to secure said pivot wire in place.

7. In a typewriting machine, the combination of a type bar support, type bars, a pivot wire for said type bars, a pivot wire tightener, and an elastic element between the tightener and the pivot wire proper, the construction being such that the amount of pressure that can be conveyed by the tightener is limited to the power of the elastic element.

8. In a typewriting machine, the combination of a type bar support, type bars, a pivot wire for said type bars, an adjustable pivot wire tightener, and an element interposed between said tightener and said pivot wire proper, said element being effective to limit the pressure conveyed by said tightener.

9. In a typewriting machine, the combination of a type bar support, type bars, a pivot wire for said type bars, a pivot wire tightener, and an elastic element controlled by said tightener and effective on the end of said pivot wire to pull it.

10. In a typewriting machine, the combination of a type bar support, type bars, a pivot wire for said type bars, said pivot wire having a threaded end, a nut adjustable on said end, and a spring element supported by said support and with which said nut coöperates.

11. In a typewriting machine, the combination of a type bar support, type bars, an arcuate pivot wire having threaded ends, nuts adjustable on said threaded ends, and yielding plates secured to said support and coöperating with said nuts.

12. In a typewriting machine, the combination of a type bar support, type bars, a pivot wire for said type bars, said pivot wire having a threaded end, a nut adjustable on said end, a spring plate, and a screw for securing said plate to said support, said spring plate coöperating with said nut to exert a pull on said pivot wire.

13. In a typewriting machine, the combination of a slotted type bar support, type bars in the slots in said support, a common pivot wire for said type bars, said pivot wire being seated in a groove in said sup-

125

130

port, a pivot wire tightener, and an elastic element between said tightener and said pivot wire, the spring being such as to press said pivot wire against one side of said 5 groove, the amount of pressure that can be conveyed by said tightener being limited to the power of the elastic element.

14. In a typewriting machine, the combination of a slotted type bar support, type 10 bars in the slots in said support, a common pivot wire for said type bars, said pivot wire being seated in a groove in said support, a spring device effective on said pivot wire, and means for varying the effect of 15 said spring device.

15. In a typewriting machine, the combination of a type bar support provided with a series of radial slots; type bars in said slots; a pivot wire seated in an arcuate 20 groove in said support; and means for variably pressing said pivot wire against the inner side of said arcuate groove, said means comprising a spring mounted on said support, and an adjustable device for va-

riably transmitting the pressure of said 25 spring to said pivot wire.

16. In a typewriting machine, the combination of a type bar support formed with an arcuate groove and provided with a series of radial slots; type bars in said slots; a 30 pivot wire seated in the arcuate groove in said support; and means for variably pressing said pivot wire against the inner side of said arcuate groove, said means comprising a pair of nuts threaded on to the ends of 35 said pivot wire, and a pair of springs secured to said support, each spring coöperative with one of said nuts to press said pivot wire against the inner wall of said groove. 40

Signed at the borough of Manhattan, city of New York, in the county of New York and State of New York this tenth day of November, A. D. 1919.

OSCAR WOODWARD.
